ADJUSTABLE HEAD LIQUID DISCHARGE
CONTROLRobert H. Pyle, Denver, Colo., assignor to
Western Filter Co., Denver, Colo.

Application October 2, 1948, Serial No. 52,550

5 Claims. (Cl. 210—30)

1

This invention relates to an adjustable feeder for feeding fluid chemical reagents more particularly for water treatment installations. The principal object of the invention is to provide a simple and highly efficient device which can be easily and accurately adjusted to deliver a continuous and uniform flow of reagent at any desired rate.

Another object of the invention is to so construct the device that the rate of flow will depend upon an adjustable head or pressure which will not vary after being preset at the desired rate.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a side view of the improved adjustable-head, fluid-discharge, control device;

Fig. 2 is a vertical section therethrough, taken on the line 2—2, Fig. 1, illustrating the device in the maximum feed position;

Fig. 3 is a reduced scale, fragmentary, sectional view of a chemical reagent reservoir, illustrating the device in place therein in an intermediate feed position.

Fig. 4 is a similar view, with the device in the minimum feed position; and

Fig. 5 is a diagrammatic sectional view illustrating the relation of the device with a chemical reagent reservoir.

In the drawing, a chemical reagent solution supply tank or reservoir is indicated at 10. In applying the device to the reservoir 10 a level compartment 34 is formed in or on the reservoir. As illustrated the compartment 34 is formed at one end of the tank and is divided from the latter by means of a partition plate 12 terminating below the top of the reservoir 10. The compartment is provided with a sub-bottom 11 positioned above the bottom of the compartment 10. A bleed port 36 communicates through the partition plate 12 immediately above the sub-bottom 11.

In use the reservoir 10 is partially filled with the treatment solution 13. This solution may be any of the usual chemical water treatment reagents such as a suspension of hydrated lime

or the like. The solution is preferably kept in agitation in any desired manner to prevent settling of the suspended particles. The agitation is assisted by constantly circulating the solution 5 through a pump 35 which intakes from the bottom of the reservoir 10 and discharges into the compartment 34 as shown in Fig. 5. The volume of solution being pumped into the compartment 34 exceeds the flow returning through the bleed 10 port 36 so that the major portion will overflow 15 the partition 12 to maintain a constant fluid level in the compartment independent of the varying fluid level in the reservoir 10. The flow through the port 36 sweeps any settled solids 15 from the sub-bottom 11.

The device, per se, comprises a hollow vertical tube 14 permanently fixed in a threaded nipple 15 so that it will project upwardly and downwardly therefrom. When installed, the 20 threaded portion of the nipple 15 extends upwardly through a receiving opening in the bottom 11, as illustrated. A clamping nut 16 is threaded onto the nipple 15 so as to clamp the nipple to the bottom 11 so as to form a watertight joint with the bottom through the medium of suitable sealing washers 17.

A metering rod 18 is positioned within the tube or jacket 14. The lower extremity of the metering rod 18 is hollow so as to form a discharge chamber 19 in the lower extremity of the rod. The lower extremity of the chamber 19 is internally threaded, as shown at 20, to receive a threaded orifice plug 21 having an external shoulder 22. The lower extremity of the metering rod is enlarged to form a shoulder portion 23 and the upper extremity of the metering rod 18 is provided with a threaded stud 26.

The threaded stud 26 is designed to receive either a metering rod extension member 27 or a finger knob 28. In Fig. 2 the metering rod extension member 27 is illustrated in place on the stud 26 and in Fig. 4 the finger knob 28 is illustrated in place thereon. The metering rod 18 and the extension member 27 are provided with spaced and numbered index marks 25, the numbers continuing in sequence from the rod 18 onto the extension member 27.

The metering rod is supported in the tube 14 by means of a cap collar 29, the lower surface of which is recessed to receive the upper extremity of the tube 14. The collar is provided with suitable set screws 30 which can be threaded into engagement with either the metering rod 18 or the extension gasket member 27 to support them 55 in the tube 14.

A flexible cup gasket 24 is clamped between the external shoulder 22 of the plug 21 and the shoulder portion 23 on the rod 18 when the plug 21 is screwed into place. The gasket 24 maintains a slidable seal against the inner wall of the tube 14.

The tube 14 is provided with inlet openings 31 adjacent its upper extremity, and the metering rod 18 is provided with outlet ports 32, communicating with the chamber 19, adjacent its lower extremity.

The openings 31 are positioned in a plane substantially opposite the top edge of the partition plate 12. The orifice plug 21 is provided with a central discharge orifice 33 of predetermined diameter. The size of the charge orifice may be varied by replacing the plug 21 with other plugs having orifices of differing sizes, so as to accommodate the conditions of the particular installation and the type of solution being fed.

As long as the pump 35 is operating, the solution level in the compartment 34 will be maintained at the top of the partition plate 12. The discharge head or pressure on the solution discharging through the orifice 33 will be determined by the distance from the orifice to the solution level in the compartment 34. This distance can be decreased so as to reduce the head by drawing the metering rod 18 upwardly through the cap 29 until the desired flow through the orifice 33 has been attained. The rod can then be set at the selected position by means of the set screws 30 to maintain a uniform feed rate.

The extension rod 27 is provided so that in cases where the metering rod 18 has been raised until it projects through the cap 29, the extension can be unscrewed and replaced by the cap so as to prevent an undue projection of the rod.

It is preferred to manufacture the tube 14 and the rod 18 from transparent plastic to avoid corrosion and so that the flow through the tube may be observed. Since the cap 29 is not secured to the outer tube 14, the metering rod can be withdrawn through the top of the tube for cleaning purposes without disturbing the setting of the rod.

While a specific form of the improvement has been described and illustrated herein, it is to be understood that the same may be varied, within the scope of the appended claims, without departing from the spirit of the invention.

Having thus described the invention, what is claimed and desired secured by Letters Patent is:

1. An adjustable device for discharging predetermined flows of liquid from a container, comprising: a vertical tube extending through, and projecting upwardly and downwardly from, the bottom of said container; said tube being formed with inlet openings adjacent the top thereof; a vertically-movable metering rod extending into said tube; a sealing gasket sealing the bottom of said rod to the inner surface of the wall of said tube; and the rod being provided with discharge passages extending from a point on said metering rod above said gasket to a point below said gasket so that liquid may flow from said tube past said gasket, portions of the discharge passages below the gasket being of less flow capacity than the inlet openings.

2. An adjustable device for discharging predetermined flows of liquid from a container comprising: a vertical tube extending through, and projecting upwardly and downwardly from, the bottom of said container; said tube being formed with inlet openings in said tube adjacent

the top thereof; a vertically-movable metering rod extending into said tube; a hollow discharge chamber in the bottom portion of said metering rod; a sealing gasket sealing said rod to said vertical tube below said hollow chamber, said rod being formed with outlet ports communicating between said vertical tube and said hollow chamber; and a plug in the bottom of said tube having a central orifice communicating between said chamber and said tube past said gasket and having a diameter less than the diameter of the inlet openings.

3. An adjustable device for discharging predetermined flows of liquid from a container comprising: a vertical tube extending through, and projecting upwardly and downwardly from, the bottom of said container; said tube being formed with inlet openings adjacent the top thereof; a vertically-movable metering rod extending into said tube; a hollow discharge chamber in the bottom portion of said metering rod; said rod being formed with outlet ports disposed about and communicating with said chamber; a threaded plug screwed into the lower extremity of said chamber; a sealing gasket slidably sealing said rod to said tube, said sealing gasket being clamped to said rod by said plug; and said plug being formed with a central orifice communicating with said chamber and being of less diameter than the inlet openings.

4. An adjustable device for discharging predetermined flows of liquid from a container comprising: a vertical tube extending through, and projecting upwardly and downwardly from, the bottom of said container; said tube being formed with inlet openings adjacent the top thereof; a vertically-movable metering rod extending into said tube through the top thereof; a sealing gasket sealing the bottom of said rod to the inner surface of the wall of said tube; said rod being formed with discharge passages extending from a point on said metering rod above said gasket to a point below said gasket so that liquid may flow from said tube past said gasket, portions of the discharge passages below the gasket being of less flow capacity than the inlet openings; a cap member on said tube, said metering rod projecting through said cap member; and means for locking said metering rod to said cap member in any desired vertical adjustment.

5. An adjustable device for discharging predetermined flows of liquid from a container comprising: an outer tube; an externally threaded nipple on said tube intermediate its extremities and adapted to contact the bottom of said container when said tube is passed upwardly therethrough; a sealing nut threaded onto said nipple and sealing the latter to the bottom of said tank; a metering rod extending into said tube through the upper end thereof and terminating above the lower extremity thereof; a sealing gasket surrounding the lower extremity of said metering rod and sealing the latter to said tube; a cap member on the upper extremity of said tube and through which said metering rod projects; rod supporting means carried by said cap and supporting said metering rod, the upper portion of the tube being formed with vertically spaced inlet openings, the lower portion of said metering rod being formed with outlet ports; a plug in the bottom of said metering rod formed with an orifice receiving fluid from said outlet ports and being of less diameter than the inlet openings.
